Filed Oct. 7, 1965, Ser. No. 87,356

Term of patent 3½ years

(Cl. D26—1)

Fig. 1.

Fig. 2.

FIG. 1 is a front perspective view of a portable test apparatus for television, showing my new design as it appears when seen from a point slightly ahead, above, and to the left of the device.

FIG. 2 is a posterior view thereof as seen from a point slightly below and to the right rear thereof.

The dominant features of my new design are shown in solid lines in the drawing.

I claim:

The ornamental design for a portable test apparatus for television, as shown and described.
